UNITED STATES PATENT OFFICE.

WILLIAM L. EPPERS AND JAMES HAMILTON, OF MOUNT WASHINGTON,
MARYLAND.

TURN-TABLE FOR USE IN MINES.

SPECIFICATION forming part of Letters Patent No. 710,851, dated October 7, 1902.

Application filed March 17, 1902. Serial No. 98,660. (No model.)

To all whom it may concern:

Be it known that we, WILLIAM L. EPPERS and JAMES HAMILTON, citizens of the United States, and residents of Mount Washington, 5 in the county of Baltimore and State of Maryland, have made certain new and useful Improvements in Turn-Tables for Use in Mines, of which the following is a specification.

In many copper, coal, and similar mines an 10 inclined shaft or passage-way is utilized for access to the ore deposits, and from such shaft galleries or levels lead off horizontally or according to the direction of the veins. It is the usual practice to lay rails in the shaft 15 and also in the galleries or levels for the cars used for conveying the mined product; but the cars which run in the shaft proper and in the galleries or levels are of different size and the tracks are of different gage. It is 20 therefore requisite that the smaller cars on the levels shall be discharged into the larger ones that run in the shaft. In other words, it is necessary that the copper, coal, or other products shall be transferred from the gallery- 25 cars to the shaft-cars. This obviously involves much time and labor and is therefore a considerable item of expense in the operation of the mine. We have devised an apparatus by which the shaft-cars may be transferred to and from the galleries or levels 30 with ease and rapidity, so that transfer of the mined product is unnecessary. In brief, a car once loaded in a gallery or level is run to the shaft and then transferred to the shaft- 35 track and hauled out of the mine. Our apparatus for effecting this result is constructed, arranged, and operated as hereinafter described, and illustrated in accompanying drawings, (four sheets,) in which—

40 Figure 1 is a vertical section of the portion of a mine, showing a section of an inclined shaft and gallery or level leading therefrom and our improved turn-table arranged at the intersection of the shaft and gallery with a 45 car thereon. Fig. 2 is a perspective view of the pivoted stop attached to the turn-table proper for holding a car thereon. Fig. 3 is a plan view representing the turn-table in horizontal position, as required to enable the car 50 thereon to run into one of the two galleries or levels shown. Fig. 4 is a view similar to

Fig. 1, save that the turn-table, with car thereon, is shown shifted to the horizontal position, as required preparatory to rotating it, so that the car may enter the adjacent gallery. Fig. 5 is a perspective view of the portion of the tiltable frame upon which the turn-table is supported, together with a spring locking device for the turn-table proper. Fig. 6 is a plan view of such tiltable 55 frame upon which the turn-table is supported. Fig. 7 is a transverse section of the turn-table and its supporting-frame. Fig. 8 is a side view of a turn-table and its frame, together with the mechanism for supporting the 60 turn-table when fixed in the inclined position parallel to the plane of the track in the shaft, as shown in Fig. 1.

Referring in the first instance to Figs. 1, 3, and 4, A indicates a shaft or passage-way, 70 having an inclination of about forty-five degrees and which in practice extends from the upper opening of a mine or from an upper chamber from which a passage-way leads outward. In practice these shafts may extend 75 several hundred feet, and therefrom galleries or levels B lead off horizontally at required intervals of space. It is the common practice to lay rails 1 in the shaft, as shown, and other rails 2 in the galleries or levels B; but they 80 are not of the same gage, or if of the same gage there is no means of transfer of cars from the shaft to the level, and vice versa. The cars used in the level B must therefore be unloaded and their contents transferred to cars 85 adapted to run on the shaft-rails 1. In the drawings, C indicates a car such as is in use in some mines for hauling up the shaft, the 90 mined product received from the cars operating in the level. We arrange at the intersection or junction of the shaft A and the level B a turn-table D, which is adapted to be shifted from an inclined position to the horizontal and also to be rotated to bring its rails 1^a into alignment with the rails 2 of the level, so 95 that the car C may be run off the turn-table into the level B or from the level on the turn-table, as required.

We will now describe the details of construction and arrangement and operation of 100 the turn-table and its several attachments.

As indicated best in Fig. 3, the table D has

a portion of its periphery or edge provided with teeth 3, adapted to mesh with a worm 3^a, which is keyed upon a shaft 4. (See Fig. 3.) This shaft has a pinion 4^a, (see Fig. 4,) that meshes with a gear 4^b, having a crank-arm 4^c. As shown in Fig. 7, the table D is supported upon a central pivot E, which forms an attachment of the frame F. (See Fig. 6.) The pivot E is provided with a ball-bearing and is otherwise constructed, as will be further described hereinafter. By rotating the worm-shaft 4 the table D may be rotated, as required, to bring the rails 1^a into alignment with the shaft-rails 1 or the gallery-rails 2. It will be seen in Figs. 1 and 3 that the shaft A is extended to form a chamber A', which accommodates the turn-table and connected parts, together with the stationary frame 34, required for supporting them and the aligned ends of the shaft-rails 1. When the turn-table D is in the inclined position shown in Fig. 1, its rails 1^a form a close joint with the shaft-rails 1, the ends of both being scarfed, as shown, for this purpose. When in this position, a car C may be run up and down on the same from or to any desired depth, the table being at such time locked in place. In practice a rope G (see Fig. 1) is run from the car C to the top of the shaft, where it is wound on a windlass operated by any suitable motor. From the inclined position the table D may be shifted to the horizontal, as shown in Fig. 4. The means for effecting this are as follows: As shown in Figs. 1 and 4, a shaft 6, having a crank 7, is provided with a worm 8, meshed with the worm-gear 9, which is keyed upon one of the trunnions 10, forming lateral extensions of the turn-table frame F. (See Fig. 6.) It is apparent that by rotating the said shaft 6 the turn-table D with its track 1^a and a car C thereon may be turned down from the inclined position to the horizontal or raised from the latter to the inclined position, as required, to enable the car C to be transferred to a level B or from the latter to the table, as the case may be. Further, the worm 8 and wheel 9 lock in any position to which they may be adjusted, and thus the table D is also locked. The gear 9 is shown mutilated. The trunnions 10 may be practically a continuous shaft extending the entire width of the frame F. The latter is provided with wheels 11, (see Figs. 1, 4, 6, and 8,) upon which the rabbeted rim of the table proper rests and travels when being rotated. The said wheels 11 therefore serve to support the table rigidly under the weight imposed upon it. We have already indicated the means 3 and 4 (see Fig. 3) for rotating the table. Such rotation is always effected when the table is in the horizontal position shown in Fig. 4, and in case the level B leads off at a right angle it is apparent that the table D will require to be rotated one-quarter around for transfer of the car. The table proper, D, is locked in position—that is to say, with its rails 1^a in alignment with the shaft-rails 1 or the gallery-rails 2—by means of the slideable spring-pin 12, (see Figs. 5, 6, and 7,) which is operated by a lever 13. The said pin 12 is adapted to slide in removable bearings 14, and a spiral spring 15 (see Fig. 7) is arranged to bear against the enlarged portion or body of said pin, it being inclosed in one of the bearings 14, as shown. The lever 13 is pivoted to the frame F, and its horizontal end extends backward, so that it may be conveniently reached by a person stationed at X, Fig. 3, where he also has access to the cranks of the shafts 4 and 6. The said spring-pin 12 is adapted to enter a socket 12^a (see Fig. 7) in the periphery of the turn-table D, and when so engaged it locks the table immovably, and thus supplements the function of the worm 3^a and shaft 4. Before the table can be rotated the horizontal end of the lever 13 is pressed inward or toward the frame F and withdraws the pin 12, and the shaft 4 being then rotated and the table thereby moved a short distance on its pivot the lever 13 is released, and the pin 12 then slides in frictional contact with the circular rabbeted edge of the table until it reaches another socket 12^a, when it is instantly thrown into the same by the spring 15.

When an empty car C is lowered into the mine, it is arrested adjacent to a gallery or level B and rests in contact with a hinged stop 16, (see Figs. 1, 2, 4,) which consists of arms secured upon a shaft 17, operated by a hand-lever 18, by which they may be thrown upward or into vertical position or downward, into alignment with the rails 1^a when not required for use. The said arms 16 are provided with sleeve extensions 16^a, by which they are supported in position to arrest the car C. The rope G being detached the crank-shaft 6 is rotated to shift the turn-table from the inclined to the horizontal position, as in Fig. 4. Then the lever 13 is operated to release the locking-pin 12 from engagement with the table, and the shaft 4 is rotated to turn the table with the car C thereon to bring the rails 1^a into alignment with the gallery-rails 2, and when this position is reached the pin 12 is automatically thrown in by the spring 15 and locks the table, as before. The empty car C is then run off into the gallery and when filled is hauled or pushed out of the same and on the table D, as shown in Fig. 3, and the table is then rotated and shifted to an inclined position, (shown in Fig. 1,) when the rope G being again attached the loaded car is hauled out of the mine. These operations—to wit, the shifting of the table horizontally and vertically, as required, to effect the transfer of empty and loaded cars—may be very easily and quickly effected.

It will be understood that the gallery B will in practice be enlarged at a point adjacent to the shaft A for the purpose of accommodating a switch or side track, as required, to enable empty and loaded cars to pass each other.

For the purpose of supporting the table D at its upper edge, so that it will have no movement vertically in consequence of looseness of other parts, we provide the mechanism shown best in Fig. 8. The same consists of a ⁵ slidable plate 20, a ¹⁰ slidable wedge 21, and a hand-lever 22. The said plate has transverse or vertical slots 23, which receive guide-pins, forming attachments of brackets 24. The lower edge of the plate 20 is horizontal, and the wedge 21, which is a long bar, slides between such bottom edge and a similarly-inclined abutment or fixed bar 25. The wedge 21 works in the keeper 26, and the lever 22 is pivoted to the turn-table frame F and provided with a lengthwise slot 22^a to adapt it ¹⁵ for the required loose connection with the wedge 21. It is apparent that by operating the lever 22 the wedge 21 may be pushed inward beneath the plate 20 or withdrawn, according as it is desired to raise or lower the said plate. When raised, the plate will abut and support the edge of the table D.

The pivot E of the table D is a screw-²⁵ threaded bolt having a flanged collar 27, (see Fig. 7,) the lower flange resting upon the anti-friction-balls 28, (see Fig. 6,) which run in a cup 29, resting upon and properly secured to the tilttable frame F. Nuts 30 are applied to the upper and lower ends of the screw E—³⁰ that is to say, above the table D and below the frame F—and cotters 31^a are applied as means for locking them. The screw 31 being firmly supported in the central cross-bar of the frame F and the flanged collar or sleeve 27 being free to rotate with the table D, it is apparent that the latter is not only greatly relieved of friction, but is duly centered on the frame at all times. The frame is suitably ³⁵ braced or trussed on its under side, as shown in Fig. 7.

In case a gallery or level B is closed or not worked the turn-table D will of course in such case be held permanently in the inclined ⁴⁵ position shown in Fig. 1. Then to strengthen the connection between the rails 1 and 1^a we apply fish-plates at their junction. (See Fig. 1, dotted lines.)

It will be seen in Fig. 1 that the lower ends ⁵⁰ of the shaft-rails 1 are supported by a brace 33, forming a portion of the general framework 34, which is arranged in the shaft enlargement or chamber A'. We have spoken of the rails 1^a as being applied to the table D. They are, in fact, however, secured to ties fastened upon timbers D', which are laid parallel and extend entirely across the upper side of the table. The lower ends of these timbers D' are chamfered or beveled, as shown ⁵⁵ in Fig. 4, so that when the table is in the inclined position they will rest or bear upon the similarly-beveled ends of timbers D^a, supporting the rails 1 in the portion of the shaft which extends below the turn-table. Further, ⁶⁰ the said beveled ends of the timbers D' close between vertical blocks 35, (see Figs. 1, 3,

and 4,) whereby the function of the table-locking devices is supplemented.

It will be understood that any preferred form of car may be employed and that the ⁷⁰ one illustrated in the drawings is used merely for illustration.

By dispensing with means for tilting the table D vertically the latter will be adapted for use on a level in or outside of a mine, and ⁷⁵ in such case the desired means for rotating the table horizontally may be dispensed with and an ordinary hand-lever used for the purpose. In brief, the table can then be used for any purpose where a turn-table is required. ⁸⁰

Having thus described our invention, what we claim as new, and desire to secure by Letters Patent, is—

1. The combination, with an inclined mine-shaft and a lateral level communicating therewith, and tracks of like gage laid in both, of a table having a track-section adapted to form part of the shaft-track or level-track as the case may be, the said table being pivoted and adapted to rotate vertically and horizontally, and means for effecting such movement, ⁸⁵ the same consisting of worm-wheels, worms, and rotatable shafts suitably geared and connected with the table and its frame, substantially as shown and described. ⁹⁰

2. The combination, with an inclined track and a lateral track arranged as shown, of a table having a track-section adapted to coincide with either of the fixed tracks, and means for rotating the table vertically, the same consisting of a worm-wheel keyed upon one of the journals of the table-frame, and a shaft and a worm carried thereon and adapted to engage the said worm-wheel, whereby the table may be rotated and locked, as shown and ¹⁰⁰ described.

3. The combination, with an inclined track, and a lateral track leading therefrom, of a table located at the intersection of the two tracks and having a track-section of the same ¹¹⁰ gage as the latter, the said table being pivoted and adapted to rotate both vertically and horizontally and provided with a peripheral rack, a gear and shaft for rotating the same which is arranged in fixed bearings on ¹¹⁵ the frame, the said gear and table-rack being relatively constructed as shown and described, whereby, when the table is shifted from the inclined to the horizontal position, the gear engages the rack and may be rotated ¹²⁰ to turn the table as required.

4. The combination, with an inclined mine-shaft and a lateral level communicating therewith and having tracks of like gage, of a table which is pivoted and adapted to rotate in ¹²⁵ vertical and horizontal planes and provided with a track-section of the same gage as the fixed tracks, worm-gearing, and two worm-shafts for operating the same, to rotate the table as required to shift it in both planes, ¹³⁰ the said shafts being provided with cranks arranged in juxtaposition, and a spring-pin

for locking the table, and a lever connected with said pin and extending into juxtaposition with the cranks of the worm-shafts, substantially as shown and described.

5. The combination, with a frame, and a table which is rotatable thereon, of a vertically-slidable plate arranged beneath the periphery of said table and adapted to engage the same when raised to a certain position, a 10 wedge arranged beneath the plate and serving to raise the same as required, and means for adjusting the wedge horizontally, as shown and described.

6. The combination, with a table, and a frame 15 upon which the same is pivoted, of a plate provided with slots and working vertically on suitable guides, a wedge arranged below said plate and adapted to be forced between the latter and a fixed piece, whereby the plate

may be brought into engagement with the 20 under side of the table for supporting it at a point adjacent to its edge, substantially as shown and described.

7. The combination, with a suitable supporting-frame, of a table and a central connecting-pivot consisting of a screw and nuts applied thereto, and a flanged sleeve or hub upon which the table is directly mounted, antifriction-balls upon which the said hub or sleeve rests and a cup or holder for said balls 25 30 fixed upon the frame, substantially as shown and described.
